DESIGN FOR A CHAIR FRAME

Frank Meyers, South Bend, Ind., assignor to Oriental Wrought Iron Works, Inc., South Bend, Ind., a corporation of Indiana

Application December 26, 1941, Serial No. 104,868

Term of patent 3½ years

To all whom it may concern:

Be it known that I, Frank Meyers, a citizen of the United States, residing at South Bend, in the county of Saint Joseph and State of Indiana, have invented a new, original, and ornamental Design for a Chair Frame, of which the following is a specification, reference being had to the accompanying drawing, forming part thereof.

Figure 1 is a front perspective view of a chair
frame, showing my new design.

Figure 2 is a side elevational view thereof; and Figure 3 is a top plan view thereof.

I claim:

The ornamental design for a chair frame, as shown.

FRANK MEYERS.
